UNITED STATES PATENT OFFICE.

WALTER A. CHURCH, OF BINGHAMTON, NEW YORK.

PUSH-BUTTON SWITCH.

SPECIFICATION forming part of Letters Patent No. 757,541, dated April 19, 1904.

Application filed June 17, 1903. Serial No. 161,838. (No model.)

To all whom it may concern:

Be it known that I, WALTER A. CHURCH, a citizen of the United States, and a resident of Binghamton, in the county of Broome and State of New York, have invented certain new and useful Improvements in Push - Button Switches, of which the following is a specification.

The invention relates to switches for controlling electric circuits, and more particularly to a switch device known in the art as a "push - button" switch—that is, a switch which may be used for making and breaking the connections of a circuit of electricity by pressing upon one of two buttons projecting from the face-plate of the switch.

The object of the invention is to provide an extremely simple device having the fewest possible number of parts and these arranged to give positive action, at the same time providing a quick make and break between the connections as the switch is opened and closed.

Referring to the drawings, Figure 1 is a view in side elevation of a switch embodying the invention with the casing or base cut in section. Fig. 2 is a detail view from the right of Fig. 1 with the bottom of the casing cut away. Fig. 3 is a perspective view of one of the stationary contact members. Fig. 4 is a sectional view on the line $\alpha\alpha$ of Fig. 1, with the switch-throwing mechanism adjusted at the highest point of the cam.

In the accompanying drawings the letter a denotes a base or receptacle adapted to receive the several parts of the mechanism comprising the switch and operating parts and the electrical connections for said parts. This base or receptacle is formed of proper insulating material and is arranged to completely inclose all parts and connections when it is inserted in a wall. The outer face of the receptacle is covered by a face-plate b of the switch, which has arranged in it openings for the push-buttons $c c'$. Secured to the face-plate is a support d , provided at one end with a cam-surface e and a recess e' , within which is arranged and adapted to slide a switch-bar

f. There are preferably two of these cam-surfaces arranged on opposite sides of the base or support. 50

Pivotaly mounted in the frame or support d , as at g , is a switch-lever h , which is preferably of T form and provided at each end of the T with pivotal connections $h' h''$, through which it is connected with the push-buttons $c c'$. The opposite end of the switch-lever h is slotted to receive a short shaft i , bearing rolls $k k'$, which coöperate with the cam-surface e for the purpose of giving a quick movement to the switch-bar f , as hereinafter described. This short shaft i is normally held at the bottom of the recess l , formed in the end of the lever h , by springs m , which are connected at their opposite ends to the support d . The switch-bar f is slotted, and the lever h projects through this slot and is provided with angularly-disposed surfaces $n n'$, which engage the ends of the slot and reciprocate the switch-bar. 60 65 70

As shown herein, the support has ledges o , forming a table upon which the switch-bar slides, and is held in proper position as illustrated in Fig. 1 and in dotted lines in Fig. 2. This switch-bar is provided at either end with contact-blades $p p'$, secured to but insulated from the bar. At either end of the receptacle are arranged stationary contacts $r r'$, insulated from each other by the base and provided at their ends adjacent to the face-plate with means for attaching the line-wires. In the form of the device shown herein there are four of these stationary contacts, the pair at each end of the receptacle forming the terminals of a separate circuit. Obviously the stationary contacts might be cross-connected in such manner as to form a three-way switch, or the same switch mechanism might be applied to a double-pole switch by simply changing the relative arrangement and number of stationary contacts. 75 80 85 90

In the operation of the device as the button c is pressed inward the lever h is tilted and carries forward the short shaft i , which rises in the slot l against the tension of the spring

g until the rolls *k k'* reach the point of the cam *e*. As soon as the rolls pass the high point of the cam the springs *m* react, pulling downward upon the short shaft and causing 5 the lever *h* to be shot forward very rapidly. As the lever makes its quick movement while the rolls are descending the face of the cam it engages the end of the slot in the switch and withdraws the contact-blade *p* from the 10 coöperating stationary contacts *r r'*, breaking the circuit. At the same time the contact *p'* is caused to engage with the stationary contacts adjacent to it.

From the above operation it will be seen 15 that there is a loose connection between the actuating-buttons *c c'* and the switch-bar, and said bar is caused to shoot backward and forward between the contacts to make and break the circuit by an extremely quick movement 20 caused by the reactive effect of the spring *m*, coöperating with the rolls and cam.

Obviously the details of the several parts might be changed without altering in any way the scope or intent of the invention, and 25 numerous changes might be made with reference to the location of contact members, &c., to provide a single-pole, double-pole, or three-way switch.

What I claim as my invention, and desire to 30 secure by Letters Patent, is—

1. In combination with a base or support, a cam immovable with respect thereto, a reciprocating switch-bar operatively mounted in the support, a lever for actuating said 35 switch-bar, means for actuating the lever, and means mounted in and carried by the lever for imparting a rapid movement to the switch-bar.

2. In combination with a base or support, 40 a stationary cam operatively mounted with relation to the base, a reciprocating switch-bar mounted on the support, a lever having a movement independent of the switch-bar, means for actuating the lever, and means 45 mounted in and carried by the lever for imparting a sudden movement to the lever and the switch-bar.

3. In combination with a base or support, 50 a lever pivoted thereto, a reciprocating switch-bar, a cam mounted upon the support, push-buttons for imparting an initial movement to the lever to move it in opposite directions, and means borne by the lever for causing a sudden secondary movement of the lever and 55 moving the switch-bar.

4. In combination with a base or support, 60 a switch-lever pivoted thereto and provided with a recess, a member transversely arranged to said lever and borne in the recess, springs for holding said member in the recess, a stationary cam operatively arranged with relation to the lever and adapted to control the

movement of the transverse member in its recess, and a reciprocating switch-bar adapted to be moved by said lever. 65

5. In combination with a base or support, a stationary cam mounted upon the support, a reciprocating switch-bar adapted to slide in said support, a tilting lever pivotally supported on said support, push-buttons for moving 70 said lever, and a roll, spring-retained in said lever and coöperating with the cam to cause a rapid movement of the switch-bar.

6. In combination with a base or support, a reciprocating switch-bar adapted to slide 75 therein and provided with a recess, an actuating-lever for said switch-bar and means for imparting movement thereto, said lever projecting through the recess of the switch-bar, a stationary cam operatively mounted with respect to said lever and switch-bar, and a spring-retained roll mounted in the lever and coöperating with the cam and adapted to impart a rapid movement to said lever and switch-bar. 80

7. In combination with a base or support, 85 a lever pivoted thereto, push-buttons and connections between said buttons and the lever for tilting the latter, a reciprocating switch-bar embracing the lever, a cam-surface arranged on opposite sides of the lever, rolls 90 mounted to move with the lever and move over the face of the cams, and springs intermediate the rolls and support for controlling the movement of the lever and switch-bar embraced thereby during the movement of the 95 rolls over the face of the cams.

8. In combination with a base or support comprising two side members, a reciprocating switch-bar mounted in said support, cams extending from each of said side members, a 100 pivoted switch-lever having a plurality of arms, push-buttons operatively connected with two of the arms of the switch-lever, a pair of rolls carried by the other arm of said lever and arranged to contact with the cams, 105 and means for holding the rolls in contact with the cams and permitting a movement of the rolls independent of the swinging movement of the switch-lever, and contacts coöperating with the reciprocating switch-bar. 110

9. In combination with a base or support including two side parts, opposing recesses formed in said side parts, a reciprocating switch-bar arranged to slide in said recesses and having an opening therethrough, a pivoted 115 switch-bar arranged between the two side parts of the support and extending through the opening of the switch-bar, a slot formed in the end of said switch-bar, stationary cams a pair of rolls supported in said slot and coöperating with the cams, springs for retaining the rolls in engagement with the cams, and push-buttons for actuating the switch-bar. 120

10. In combination with a support, a sta-

tionary cam mounted on the support, a reciprocating switch-bar arranged to slide in the support and provided with an opening, a pivoted switch-lever having a plurality of arms, 5 push-buttons connected with two of said arms, a coöperating member borne in and moving with the other of said arms, and means for retaining it in engagement with the switch-

lever, and angularly-disposed surfaces upon opposite sides of the switch-lever arranged to engage and move the reciprocating switch-bar.
